UNITED STATES PATENT OFFICE

125,282

DESIGN FOR A STUD BUTTON OR SIMILAR ARTICLE

Mortimer Marcus, New York, N. Y.

Application December 21, 1940, Serial No. 97,543

Term of patent 3½ years

To all whom it may concern:

Be it known that I, Mortimer Marcus, a citizen of the United States of America, residing in the city of New York, county of New York, and State of New York, have invented a new, original, and ornamental Design for a Stud Button or Similar Article, of which the following is a specification, reference being had to the accompanying drawing, forming part thereof.

Fig. 1 is a plan view of a stud button or similar article showing my new design.

Fig. 2 is an edge view thereof.

I claim:

The ornamental design for a stud button or similar article, as shown.

MORTIMER MARCUS.
